IRONING MACHINE

William H. Bradley, Fort Wayne, Ind., assignor to
Horton Manufacturing Company, Fort Wayne,
Ind., a corporation of Indiana

Original application June 19, 1940, Serial No.
341,220. Divided and this application March
25, 1943, Serial No. 480,433

5 Claims. (Cl. 38—60)

The invention relates generally to ironing machines and more particularly to an ironing machine of the roll and shoe type.

This application is a division of my copending application, Serial No. 341,220, filed June 19, 1940, issuing on January 4, 1944, as Patent No. 2,338,163.

The general object of the invention is to provide a novel ironing machine of the roll and shoe type, of such size and weight that it may be easily lifted and placed on any available table suitable for the work, which has a capacity equal to or nearly equal to much heavier power-actuated ironing machines for domestic use, and which is of relatively simple and inexpensive construction, thus making it particularly advantageous for ordinary household use.

Another object is to provide in an ironing machine a novel mounting of the motor and gearing for driving the roll, which conceals the motor and the gear casing and which facilitates the assembly of these parts of the machine.

A further object is to provide in an ironing machine a novel driving connection between the motor and the shaft supporting the roll, which includes a simplified pawl and ratchet drive permitting the roll to be turned forwardly by hand to facilitate placing an article between the roll and shoe.

Other objects and advantages will become apparent from the following description taken in connection with the accompanying drawing, in which:

Figure 1 is an end view on a reduced scale of an ironing machine embodying the features of the invention.

Fig. 2 is a vertical section taken on the line 2—2 of Fig. 3.

Fig. 3 is a vertical section through the axis of the roll.

Fig. 4 is a vertical section taken on the line 4—4 of Fig. 3.

Fig. 5 is a fragmentary perspective view showing a portion of the roll drive mechanism.

The ironing machine disclosed herein is of the roll and shoe type and comprises generally a base, indicated at 10, and a support, indicated at 11, located at one end of the base for supporting a roll 12. Coacting with the roll is a shoe 13 shiftably supported intermediate its ends by means indicated generally at 14. The shoe supporting means 14 is shiftable to move the shoe toward and from the roll and is operated by a hand lever extending upwardly and over the shoe and roll. Thus the hand lever occupies a position

convenient to the operator and will not be covered up by articles being ironed which extend beyond the ends of the roll. The roll is rotated by means of a motor, the circuit for which may be controlled as an incident to the operation of the shoe shifting means 14, so that the roll remains stationary when the shoe is out of contact therewith and will be rotated when the shoe and roll are in engagement, as shown in said application Serial No. 341,200.

The invention disclosed and claimed herein relates to the manner of supporting the roll and the structure of the means for driving it. Generally described, the support 11 extending vertically from the base 10 is provided at its upper end with a hollow head adapted to support the roll driving mechanism and to house a portion of it. Thus I provide a gear casing of two-part construction having a motor secured to one of said parts. The gear casing is adapted to be secured to the head adjacent one end thereof which is open, and the parts are so positioned that the motor is located within the head and the gear casing outside thereof. The two parts of the gear casing are secured together and the motor is attached thereto, in a unitary arrangement, and then they are assembled onto the head, the means for securing the gear casing to the head additionally securing the two parts of the casing together.

The motor is provided with a small fan located within the head, and vents are provided in the head so that a current of air may be forced therethrough to keep the motor cool.

The motor is connected to gearing within the casing and a roll supporting shaft extends outwardly from the gear casing. The roll is so formed that it extends back over the gear casing and telescopes for a short distance over the head. Thus the gear casing and motor are entirely concealed.

The motor drives the gearing within the casing and the gearing includes a pinion mounted on a stub shaft and meshing with a gear on the end 45 of the roll shaft. Mounted on the same stub shaft as the pinion is a gear connected with the motor and provided on one face with a pawl for driving the pinion. To this end, the pinion is made long enough to mesh with the gear on the roll shaft and to provide a portion to cooperate with the pawl. By such construction the one part, namely, the pinion, serves as a ratchet and as a drive for the gear on the roll shaft, thus simplifying the construction by reducing the 50 number of parts. The ratchet drive of the pin-

ion permits the roll to be turned forwardly by hand at any time. Thus during the placing of an article on the roll to be ironed, the roll may be turned to move the front edge of the article into the space between the roll and shoe to facilitate starting the article through the machine.

As shown in the drawing, the preferred embodiment comprises a head 20 on the upper end of the support 11. Preferably the head 20 and support 11 are made in an integral casting, and the head 20 is of generally ogival form to provide a neat appearance. The head 20 is provided with a plurality of vents 21 at its outer or right end, as shown in Fig. 3, while its left end is open, as shown in said figure.

Adjacent the open end of the head 20 is a closed gear casing of two-part construction comprising a casing proper, indicated at 22, and a cover 23. To reduce the number of parts, the gear casing 22 and the cover 23 are secured together by the means employed to secure the gear casing to the head 20. Thus I provide a plurality of ears 24 on the gear casing 22, a corresponding number of ears 25 on the cover 23, and also a corresponding number of ears 26 on the head 20. I then secure the three sets of ears together by bolts 27. The gear casing is thus located adjacent the open end of the head 20 but outside of the head.

A motor 30 is provided for driving the roll, which motor is preferably located within the hollow head 20. The motor is preferably secured to the gear casing, and as shown, is mounted on the cover 23 and is secured thereto by bolts 31. The motor thus is located within the head 20 and in a concealed position. The motor on its end opposite the gear casing carries a fan 32 to produce a current of air for keeping the motor cool. The fan 32 thus is located within the head 20 where it is out of the way, and an airflow is created through the head, the current passing through the vents 21 and the open end of the head.

To facilitate assembly of the parts, the gear casing 22, the cover 23, and the motor 30 are all secured together as a unit before being attached to the head 20. Thus the bolts 31 permit the motor 30 to be secured to the cover 23. The casing 22 and the cover 23 are provided with additional ears 33 with a bolt 34 extending therethrough, which holds the two parts together sufficiently to permit its assembly to the head 20. Thus the bolt 34 secures the casing and cover together independently of the bolts 27 so that the gear casing, cover and motor are all assembled together as a unit before being secured to the head 20.

The gear casing has extending therefrom a roll supporting shaft 35 arranged to have secured thereto a pair of dished members 36 supporting the roll 12. The dished members 36 are located inwardly from the ends of the roll so that one end of the roll extends completely over the gear casing and telescopes a short distance over the head 20, as shown clearly in Fig. 3. Thus the motor and gear casing are completely concealed within the roll and the head so that the construction presents a neat appearance.

Another feature of the invention lies in the simplified construction of the gearing within the gear casing, which connects the motor 30 with the roll shaft 35. This gearing is of the reduction type to reduce the motor speed down to the speed proper for rotation of the roll. In an ironing machine it is desirable to be able to freely

rotate the roll in a forward direction by hand either when the roll is stopped or when it is being driven by the motor. Thus when an article to be ironed is placed upon the roll it is sometimes more convenient to place the advance edge of the article along the top of the roll, then turn the roll by hand forwardly to bring the edge of said article into the space between the roll and shoe, at which time the shoe is shifted into contact with the roll and the clamping action therebetween causes the article to be continued to be drawn in for ironing. For this purpose the roll driving mechanism is provided with a one-way drive so that the roll may be freely turned forwardly. In the present instance the one-way drive is in the form of a ratchet.

More specifically, the gearing for driving the roll includes a driven gear 40 (see Figs. 3 and 5) mounted on the end of the roll shaft 35 and within the gear casing 22. Mounted on a stub shaft 41 within the gearing casing is a pinion 42 adapted to drive the gear 40. To drive the pinion, there is a gear 43 mounted on the stub shaft 41 and connected through other gears with the motor. The gear 43 is free to rotate relative to the pinion 42, and to connect the two, a ratchet drive is provided. To simplify the construction, the pinion 42 is substantially longer than is necessary merely to mesh with the gear 40 to provide a portion adjacent the gear 43. Mounted on the face of the gear 43 is a pivoted pawl 44 which is spring-pressed toward the pinion 42 to engage between the teeth thereof and thereby effect a driving relation. When the roll is rotated forwardly by hand, the pinion 42 rotates in such direction as to force the pawl out of the way against the pressure of its spring, thus permitting the roll to be freely turned. However, the pawl 44 engages between the teeth of the pinion when the roll is driven forwardly by the motor. Since the pinion 42 may be manufactured in the length shown in the drawing at not much more cost than if it were only long enough to mesh with the gear 40, the cost of an additional ratchet is thereby eliminated.

From the foregoing, it will be apparent that I have provided an ironing machine which is of relatively simple and inexpensive construction and particularly advantageous for use in the ordinary household. The motor and gear casing are entirely concealed, partly within the roll and partly within the head 20, so that the machine has a neat appearance. The assembly of these parts is made easy by virtue of the fact that the gear casing and its cover, together with the motor may all be assembled together as a unit before being secured to the head. The driving connection between the motor and the roll supporting shaft is simplified by utilizing a single member, namely, the pinion 42, to serve both as a drive for the gear 40 and as a ratchet wheel.

I claim as my invention:

1. In an ironing machine, the combination of a vertically extending fixed support including a hollow head having an open end, a two-part gear casing, means for securing the two parts of the gear casing together and for securing them to the open end of said head in close proximity thereto, a motor rigidly secured to one of said parts and located within said head, whereby the weight of the motor is vertically aligned with said support and the weight of the gear casing is closely adjacent thereto, and a roll supporting shaft extending from the other of said parts.
2. In an ironing machine, the combination of a

vertically extending fixed support including a hollow head having an open end, a gear casing having an open end, a cover for the open end of the gear casing, means for securing the gear casing to the open end of said head and clamping said cover therebetween, a motor mounted on said cover and positioned within said hollow head, whereby the weight of the motor is vertically aligned with said support and the weight of the gear casing is closely adjacent thereto, and a roll supporting shaft extending from the gear casing.

3. In an ironing machine, the combination of a base, a fixed support extending upwardly from said base and having at its top a hollow head having an open end, a roll telescoped over said open end, a gear casing rigidly secured against said head at said open end and located within the roll, a motor mounted on said gear casing and located within said head, whereby the weight of the motor is vertically aligned with said support and the weight of the gear casing is closely adjacent thereto, and a shaft supporting said roll and extending from said gear casing.

4. In an ironing machine, the combination of a fixed vertical support including a hollow head having an open end, a roll adjacent said open

end, a gear casing and a motor secured together as a unit, and a roll supporting shaft extending from said gear casing, said gear casing and motor being secured to the open end of said head with the motor located within the head and the gear casing outside of the head, the roll being mounted on said shaft and extending over said gear casing, the unitary arrangement of the gear casing and motor permitting operative assembly and adjustment thereof before securing the unit to said support, and said unit being adapted to be secured to said support in operative position before securing the roll to said shaft.

5. In an ironing machine, the combination of a fixed support including a hollow head having an open end, a two-part gear casing, means for securing said two parts together independently of the mounting of the gear casing, a motor secured to one of said parts, whereby said gear casing and motor may be assembled in operative relation prior to securing them to said head, and means for securing said gear casing to said head with the motor inside and the gear casing outside the head, said last-mentioned means additionally securing the two-parts of the gear casing together.

WILLIAM H. BRADLEY.
